UNITED STATES PATENT OFFICE.

HENRY D. T. BRANTON, OF FORT SCOTT, KANSAS.

REVERSIBLE BEVEL-SHAPER, SAW, AND BORING-MACHINE.

SPECIFICATION forming part of Letters Patent No. 379,930, dated March 27, 1888.

Application filed March 14, 1887. Serial No. 230,912. (No model.)

To all whom it may concern:

Be it known that I, HENRY D. T. BRANTON, a citizen of the United States, residing at Fort Scott, in the county of Bourbon and State of 5 Kansas, have invented a Reversible Bevel-Shaper, Saw, and Boring-Machine, of which the following is a specification.

My invention is a new wood-working machine, in which the material to be worked is 10 operated upon by means of suitable cutters attached to a revolving arbor; and the objects of my improvements are, first, to provide an arbor arranged to have a rotary, reversible, radial, and vertical movement; second, to afford facilities for properly adjusting the arbor 15 to work at any angle from horizontal to vertical; third, to apply the belting so that it may be retained on the pulleys at a proper tension and be automatically adjusted to the varying 20 positions and angle of the arbor; fourth, to secure a means of adjusting the slot or opening in the table-top with reference to saws or cutters on the arbor, and, fifth, to construct the table-top in such a manner that part of it 25 may be used as a boring-table with lateral and vertical motion in conjunction with a revolving arbor for boring and routing. I attain these objects by the mechanism illustrated in the accompanying drawings, of 30 which—

Figure 1 is a top view of the machine as it appears with table-top removed, showing cut sections of important parts. Fig. 2 is a right-side elevation with part of frame broken 35 away, showing mechanism for manipulating the arbor and the method of belting over binder-pulleys. Fig. 3 is a plan with table-top removed, showing arrangement of mechanism for operating arbor 13. Fig. 4 is a section on 40 line A B, Fig. 3, showing driving-pulley 10, binder-pulleys 28 29, and means for vertically adjusting arbor 13. Fig. 5 is a front elevation showing mechanism for radially adjusting arbor 13. Fig. 6 is a front elevation showing 45 split bearing 14 on apron 15 and mechanism for vertically adjusting same. Fig. 7 is a rear elevation of driving-pulley 10, binder-pulleys 28 29, and means for automatically adjusting the belts. Fig. 8 is a plan of table-tops 41 and 50 42, showing in dotted lines the recess for sliding pieces 54 and 55. Fig. 9 is a left-side elevation showing vertical adjustment of apron

43 and lateral adjustment of table 42 on slides 45 and 46. Fig. 10 is a group of views showing construction of guide 58 and slide 60 in 55 claim 6.

The frame is constructed as shown by 1 and 2, Figs. 1, 2, 3, and 4. In bearings on frame 2 turns the shaft 3, carrying cone friction-pulleys 4 and 5, the flat driving-pulley 6, and reversing lever and collars 7. The shaft 8, running in bearings on frames 1 and 2, carrying cone friction-pulley 9 and grooved driving-pulley 10, is caused to revolve in opposite directions by cone-pulleys 4 and 5 being brought 60 in frictional contact with opposite sides of cone-pulley 9 by means of reversing lever and collars 7 on shaft 3, working in thrust-block 11, bolted to frame 2.

The yoked bearing 12, in which revolves 70 the arbor 13, is provided with a journal turning in a split bearing, 14, on apron 15, and can be fastened rigidly therein by means of clamp-levers 16 16, on one end of which journal is secured a worm-gear, 17, operated by 75 worm 18 and hand-wheel 19, so that by turning hand-wheel 19 a radial motion is imparted to arbor 13, Figs. 1, 2, and 4.

The apron 15 is adapted to slide on frame 1, and has a vertical motion thereon through the 80 medium of hand-wheel 20, miter-gears 21 22, and screw-rod 23, working in threaded lug 24 on connecting-bar 25, so that by turning hand-wheel 20 a vertical motion is imparted to arbor 13. The apron 15 is adjusted to take up lost 85 motion by set-screws 27, Figs. 2 and 4.

The grooved binder-pulleys 28 29 are fastened to spindles turning in bearings on pivoted arms 30 31, Figs. 2 and 3, said arms having a journal or pivot formed on their lower ends, 90 and which swivel in suitable bearings, 32 33, on sliding rack 34. This sliding rack is adapted to a slide, 35, on the inside of frame 1, and is moved horizontally thereon by a pinion, 36, gearing into rack 34. Said pinion is 95 secured to a shaft turning in a bearing, 37, on frame 1, and having fastened on its outer end a rope-wheel, 38, carrying a weight, 39, Figs. 3 and 5.

Round belts 40, fitting into suitable grooves 100 in driving-pulley 10, passing over grooved binder-pulleys 28 29 and around the grooved pulley on arbor 13 and driven by the reverse-motion friction-pulley 9, cause the arbor 13

to revolve in either direction, the belts 40 being retained in position and proper tension through the medium of the automatically-adjusting binder-pulleys 28 29, Figs. 2 and 3.

5 The table-top 41 42 is made in two pieces, the largest piece, 41, being bolted rigidly to frames 1 and 2, the sliding piece 42 having a vertical and lateral movement.

The apron 43 is fitted to vertical ways 44 to on frame 1, and is provided with horizontal bracket-slides 45 46, on which the movable table-top 42 is secured by gibbs 47 48. Said apron 43 is moved vertically by hand-wheel 49, secured to a shaft on which is fastened a 15 miter-gear, 50, meshing into a like miter-gear, 51, on screw-rod 52, working through threaded lug 53 on frame 1, Figs. 1 and 3.

In the table-tops 41 42 is a recess extending across both sections, into which is fitted corresponding sliding pieces, 54, that can be fastened in said recesses in any required lateral position by bolts and thumb-nuts, as 56. The sliding pieces 54 are separated to receive between them a third sliding piece, 55, having a 25 circular hole in it, through which projects the shaper-spindle 57 on arbor 13, when used for shaping. All of sliding pieces 54 55 may be moved laterally across the tables 41 42, thus affording an adjustable slot in table for square 30 or bevel sawing, dadoing, &c., and an adjustable circular opening, 55, to accommodate arbor 13 when used as a vertical or bevel shaper, Fig. 3.

The guide 58, Figs. 3 and 4, is furnished with 35 two pins on its under side and lug on its end, and is placed on tables 41, the pins fitting into two rows of holes bored in the table to receive them, thus preventing any side motion of guide 58, which is clamped down by thumb-screw 59, as shown, Figs. 3 and 4. It is used in connection with slide 60 for crosscutting, 40 mitering, dadoing, &c. The cut-off slide 60, the fence of which is made to swivel, is adapted to guide 58 and table 41, on which it slides.

45 The ripping-gage 61 has an arm sliding through frame 62, in which it is fastened by thumb-screw 63. Said frame is also provided on the under side with two pins like those on guide 58 and fitting into the same holes in 50 table 41 42, and may be used on either side of the saw.

I am aware that prior to my invention there have been made reversible shaping-machines in which friction cone-pulleys have been used, 55 also a ripping-gage and cut-off slide somewhat similar to those herein described. I therefore do not claim these as my invention; but

What I do claim as my invention, and desire to secure by Letters Patent, is—

6c 1. In a reversible bevel-shaper and boring-machine, the combination of shaft 8, carrying

grooved reversible driving-pulley 10, reversing friction cone-pulleys 4, 5, and 9, with the grooved binder-pulleys 28 and 29, the pivoted arms 30 31 in their bearings 32 33 on sliding 65 rack 34, moving on slide 35 on frame 1, the pinion 36 and rope-wheel 38 on shaft turning in bearing on frame 1, and weight 39, the round belts 40, and the arbor 13, with grooved pulley and saw or tool thereon, all substantially 70 as and for the purpose set forth.

2. The combination of the grooved pulley 10, the sliding rack 34, slide 35 on frame 1, the pinion 36, rope-wheel 38, and weight 39, with belts 40, apron 15, sliding on vertical slides 75 26 on frame 1, the split bearing 14 on apron 15, clamp-levers 16, the journaled yoke-bearing 12, the arbor 13, worm-gear 17, worm 18, hand-wheel 19, hand-wheel 20, miter-gears 21 22, screw-rod 23, and threaded lug 24, substantially 80 as and for the purpose shown and described.

3. In a reversible bevel-shaper and boring-machine, an arbor, 13, provided with a grooved pulley, in combination with means 85 for giving to the arbor four distinct motions, as rotary and reverse motions, consisting of round belts 40, operating on pulley on arbor 13, binder-pulleys 28 and 29, and the reversible grooved driving-pulley 10, and radial and 90 vertical motions consisting of apron 15, split bearing 14, clamp levers 16, yoke-bearing 12, worm-gear 17, worm 18, hand-wheels 19 20, miter-gears 21 22, screw-rod 23, and lug 24, as set forth, all mounted in frame 1, substantially 95 as and for the purpose shown and described.

4. In a reversible bevel-shaper and boring-machine, the combination of the tables 41 and 42, the sliding pieces 54 55, and bolts and thumb-nuts 56, in conjunction with arbor 13, 100 the yoke-bearing 12, split bearing 14, clamp-levers 16, apron 15, worm gear 17, worm 18, hand-wheels 19 20, miter-gears 21 22, screw-rod 23, lug 24, and slides 26 on frame 1, for manipulating said arbor 13, all substantially 105 as shown and specified.

5. The combination of the four-motion arbor 13, the apron 43, hand-wheel 49, miter-gears 50 51, screw-rod 52, threaded lug 53, and vertical ways 44 on frame 1, and the table 42, 110 moving on bracket-slides 45 46, substantially as set forth.

6. In a reversible bevel-shaper and boring-machine, the combination of the guide 58, secured by thumb-screw 59 to tables 41 or 42, on 115 which is moved slide 60, in connection with reversible arbor 13.

HENRY D. T. BRANTON.
